GEORGE SEYMOUR, OF PHILADELPHIA, PENNSYLVANIA, ASSIGNOR TO VELCUT COMPANY, INC., A CORPORATION OF PENNSYLVANIA.

MACHINE FOR CUTTING PILE FABRICS.

Application filed May 12, 1922. Serial No. 560,277.

My invention relates to improvements in pile cutting devices for use on looms for weaving pile fabrics wherein the pile is formed of floats of weft threads over pile wires or other suitable leaders which extend in the direction of the warp.

A principal object of my invention is to provide a pile cutting device suitable for connection to the pile wires or leaders and operative to cut the pile as rapidly as the float is fed to the cutters as the fabric is produced by the loom, the cutting operation being effected as the fabric is passing from the point at which it is woven to the take-up roll of the loom on which it is wound.

A further object of my invention is to provide a machine for the performance of the aforesaid function which is of novel, simple and efficient construction and which is adapted for cutting the floats of the fabric even when the floats are positioned very closely together, thus facilitating the production of very fine pile fabrics, and which is additionally operative to cut each of the loops of the float at its center so that the individual yarns forming the pile in the finished fabric will be all of substantially the same length.

Still further objects of my invention are to provide a machine of the character aforesaid embodying in its preferred form a plurality of circular cutters arranged in two separate series, the cutters in one series being effective to cut every other float or row of loops and the cutters in the other series being effective to cut the other rows, and having means for permitting the removal or insertion of individual cutters in either series without disturbing the other cutters thereof, as well as means for effecting adjustment of the individual cutters to bring them into proper alignment with the float on which they are operative, and generally to so arrange the cutters and other elements of the machine as to permit its use with pile wires or other forms of leaders and with different types and shapes of cutter noses, thereby facilitating the production of various sorts of pile fabrics.

The invention further comprehends the provision of novel means of simple and efficient design and construction for actuating

the cutter driving mechanism from the lay of the loom, said means being effective to convert the reciprocating motion of the lay into suitable rotary motion for actuating the cutter driving shafts.

In addition to the several objects to which reference has hitherto been made, my invention further includes all of the other objects and various novel features of construction and arrangement hereinafter more particularly referred to or which will be apparent from the following description taken in connection with the accompanying drawings forming a part hereof.

While for the purpose of effecting the objects and functions of my invention I may employ any suitable means and instrumentalities, I have illustrated in the accompanying drawings and will now proceed to describe a preferred embodiment of means suitable therefor, and as the invention is adapted for operative attachment to and for use in connection with a loom I have, in the said drawings, shown such parts of a loom, which may be of any suitable form and construction, as are requisite for a proper comprehension of the invention.

In the said drawings, Fig. 1 is a fragmentary rear elevation of a preferred form of the invention showing the same in operative association with the beam of the loom and also showing a few of the cutters in one of the series with their adjacent mechanism. Fig. 2 is an end elevation of the right hand end of the machine viewed as in Fig. 1, and Fig. 3 a similar elevation of the left hand end thereof. Fig. 4 is a view substantially similar to Fig. 3 but showing the parts in the position assumed during the operation of removing or inserting individual cutters. Fig. 5 is an enlarged partially fragmentary detail view showing one of the cutters in operative position together with its associated driving mechanism. Fig. 6 is a vertical section on line 6—6 in Fig. 5 looking in the direction of the arrows; Fig. 7 is a horizontal, central section through certain of the cutters of both series showing the same in operative position and in association with pile wires, this view being on a slightly smaller scale than Figs. 5 and 6, and Fig. 8 is a perspective view of a cutter nose removed from the cutter. Fig. 9 is a central vertical

section on an enlarged scale of a preferred means for driving the cutters and which for convenience I shall hereinafter term the motor, and Fig. 10 is a vertical transverse section thereof on the line 10—10 in Fig. 9 looking in the direction of the arrows.

Generally speaking the machine comprises a pair of end plates which are attached to the beam B of the loom and between which are arranged two series of cutters with their respective supporting means one behind the other, but with the cutters of the rear series, that is, the series at the right hand side of Fig. 3 and which is farthest from the loom, in aligned relation with the spaces between the cutters in the forward series. Means are also provided for effecting the drive of the cutters comprising a transversely extending drive shaft adjacent each series of cutters supported in movable journal housings carried by the end plates and having a driving gear cooperative with a pinion actuated by the motor, which latter is positioned outside of and adjacent one of the end plates, and a plurality of individual driving gears mounted on each shaft and each cooperative with an adjacent cutter. It will be understood that all of the cutters in both series are preferably similar to each other and that the driving means and cutter supporting means in association with each series are substantially similar to the corresponding means of the other series; I have therefore for convenience of description and to avoid needless repetition hereinafter referred more particularly to the forward series of cutters and associated means designating the corresponding parts adjacent the other series by the same numerals but with the addition of a prime ('). Consequently, such portions of the following description as are directed more particularly to the forward series of cutters and their holding and driving means, is equally applicable to the rear series with their corresponding parts and is to be understood as applying equally thereto.

More particularly, the machine in its preferred embodiment comprises a pair of end members 2 and 3 respectively provided with horizontally disposed bases 4 and 5 which may be operatively attached by screws 6 to the upper side and adjacent the ends of the beam B of the loom, and with downwardly directed flanges 8 and 9 arranged to abut the rear face of the beam to assist in securely and properly positioning the members thereon. The plate 2 comprises a pair of longitudinally separated, upwardly extending lugs or horns 10, 10' and the plate 3 a similar pair 11, 11', while each plate is provided with inwardly directed flanges 13, 13', 14, 14' which respectively serve to support the transversely extending bars 15, 15' secured thereto by bolts 16 and which serve in turn to support the cutters as will hereinafter appear. The

under faces of these bars are preferably raised above the plane of the top of the beam so as to afford a space 17 for the passage of the fabric.

Extending between the end members are the cutter drive shafts 18, 18' which are positioned one behind the other and normally supported vertically above the respective series of cutters. Each of these shafts extends slightly beyond the outer faces of the end members and is journaled, preferably on annular ball bearings 19, in housing plates 20 and 21, conveniently of substantially diamond shape as shown, which are pivoted at their lower ends on pivot screws 22 and 23 extending into the members, the screws 22' and 23' being arranged at a suitable distance in the rear of the screws 22 and 23. The upper extremities of the housing plates 20 and 21 are tied together by a transversely extending tie rod 25 and the corresponding ends of the plates 20', 21' similarly tied by a rod 25', the ends of these rods being respectively reduced in diameter and extended through the ends of the adjacent housing plates and nuts 26 and 27 being positioned on the projecting ends of the rods to retain them in position. The tie rods are arranged to engage against the forwardly overhanging ends of the adjacent horns 10 and 11 which extend upward from the end plates, and overhanging latches 28 and 29 are pivotally secured to the upper ends of the horns by pivot screws 30 in such manner that they can be turned down to engage over the adjacent tie rod, as clearly shown in Figs. 2 and 3, each latch being provided with a set screw 31 extending through the free end of the latch in such manner that when the latch is turned down over the rod the set screw may be screwed inwardly so as to force the rod tightly against the face of the adjacent horn, thus firmly securing the rod in position against the horn, and in turn supporting the housing plates in substantially vertical or normal operative position. It will be evident, however, that by loosening the set screws in both latches adjacent either rod, the latches may be turned up away from the rod to permit the rod and housing plates to be swung downwardly and forwardly, for a purpose to be hereinafter described, until further movement is arrested by stop pins 33, 34 suitably positioned in the end members.

Each of the drive shafts 18, 18' is provided at one end, conveniently the right hand end as viewed in Fig. 1, with a gear 36 keyed or otherwise secured to the shaft and prevented from longitudinal displacement thereon by a large-headed screw 37 countersunk into the face of the gear and extending into the shaft or in any other convenient way, and positioned between these gears in such manner as to engage and drive both of them when

the housing plates are in upright or normal position is a main driving pinion 40 which is mounted and actuated in a manner hereinafter described. A relatively narrow shield 42 having forwardly and rearwardly extending wings or arms is preferably removably positioned above the several gears, the shield being conveniently provided with a downwardly extending lug 43 adapted to enter a socket 44 formed in a lug 45 integral with the housing of the motor or other convenient part, a knob 46 carried by the shield providing a convenient means of lifting the latter in and out from the socket when it is desired to remove the shield to expose the gears.

Each of the cutters comprises a circular blade 50 of thin tempered steel or other suitable material which may be sharpened at its outer edge as at 51 and to one face of which is secured a gear 52, as by the rivets 53, the gear being of somewhat less diameter than the blade. Both the gear and the blade are pivotally secured by means of a suitable pivot 55 to the cutter body 56 which is formed from thin metal or the like and shaped as best shown in Fig. 5 so as to provide a main portion 57 for the passage of the pivot and which partially overlays one side of the blade and a rear portion 58 which extends rearwardly beyond the periphery of the blade and is preferably laterally offset so as to bring it more nearly into alignment with the blade. The lower part of the rear portion of the cutter body terminates in a foot 59 from which the rear edge of the body is directed angularly rearward and upward as at 60, the body terminating in a head or block 62 provided with a groove 63 in its under face which is operative to engage over a rib 66 formed along the forward edges of the bars 15, 15', as clearly shown in Fig. 5, the upper surface of the rib being positioned below the upper surface of each bar for a distance preferably equal to the height of the head or block of the cutter body at that point, so that the upper edge of the latter is in substantial alignment with the upper surface of the bar when the head is engaged over the rib. Preferably in order to assist in more securely positioning the cutter body in the bar, I rivet or otherwise secure to the side of the head a piece of metal 64 shaped in conformity with the head and which I term the balance piece, thereby thickening the head and giving more surface for engagement with the means provided for holding it in operative position.

For holding the cutter bodies and in turn the cutters in position on the bars 15, 15', I provide each of the latter with a plurality of clamping blocks 68, each of which is preferably equal in width to the width of the bar from front to back and is removably secured thereto by a bolt 69 extending through

the block and down into the bar. While the blocks 68 may be of any desired length, I prefer to make them relatively narrow so that each of them will be operative to overlie but a relatively small number of the cutter bodies, for example, eight or ten, so that by removing any one of the blocks the clamping pressure on only those cutter bodies which are subjacent to that particular block will be relieved.

The lower part or foot of each cutter body is adapted for operative connection with a suitable leader, this connection where the leader is in the form of a pile wire being preferably made through the medium of a member, a preferred form of which is best shown in Fig. 8. This member comprises a body portion 70 having flat vertically extending sides 71, 72 spaced apart for a distance equal to the thickness of the cutter body foot 73 and joined together at the bottom. At its forward end each of the sides, which are preferably somewhat longer than the foot of the cutter body, are curved downwardly as at 74 and cut away so as to leave only a very thin forwardly projecting strip of metal 75 integral with each side and together forming a split nose, these strips being laterally sprung out or curved in opposite directions and merging together at 76 adjacent the forward extremity of the nose which is there provided with an eye 77 for attachment of the pile wire W. One of the body walls 70 is preferably provided with a notch 78 for the reception of a laterally projecting pin 79 which is carried by the foot and which enters the notch when the nose is positioned on the foot and assists in maintaining it in proper position thereon. It will be observed that by reason of the outward swelling of the part 74, the overall width of this part of the nose is considerably greater than its width adjacent the body portion 70 or at its forward extremity 76. The purpose of this lateral enlargement of the split portion of the nose will hereinafter more clearly appear.

Each of the cutters 50 is individually driven from its adjacent driving shaft through the medium of a gear 80 adapted for cooperation with the gear 52 carried by the cutter and which is secured to a guide disk 81. This disk is disposed alongside of the gear but has the major portion of its peripheral margin spaced or offset therefrom so as to provide a guide slot 83 between the adjacent faces of the gear and the disk, this slot being of suitable width for the reception of the cutter blade when the gears are in intermeshed relation as best shown in Figs. 5 and 6. The gear and the guide plate are each provided with a central aperture for the passage of the drive shaft, a convenient method of securing the plate and gear together being, as best shown in Fig. 6,

to bend the inner marginal edge of the plate over the corresponding edge of the gear so as to embrace the latter, in which case the turned over part 84 of the guide plate will form a bearing surface for engagement with the shaft. Additionally, if desired, the gear and plate may be brazed together or otherwise united. The drive shaft is provided with a longitudinally extending keyway 86 and the plate with a cooperating key or tongue 87 adapted to engage therein so that when the operatively unitary gear and plate are disposed on the shaft they are constrained to rotate therewith; the position of the shaft with respect to the subjacent cutters being such that the upper part of each cutter will, under operative conditions, enter the slot 83 between the plate and the driving gear to thereby retain the gears 52 and 80 in proper mesh and the parts in properly aligned relation.

For effecting actuation of the cutter driving shafts, I prefer to employ the mechanism now to be described and which for convenience I term the motor, since by doing so I am enabled to utilize the reciprocating motion of the lay of the loom and to convert the same into a suitable rotary motion which, through the medium of the pinion 40, is transmitted to the driving shafts. It will of course be understood that during the weaving operation the lay with which the loom is provided, and which is not shown on the drawing, is constantly moved toward and away from the beam B in the ordinary manner well known in the weaving art, and for the purpose of transmitting this motion to the motor I preferably employ a belt 90 of canvas or other suitable material which extends from the lay, to which it is suitably secured, through an opening 91 in the wall of the motor housing 92 as best shown in Fig. 10. This housing which is provided with feet 93 is supported upon and rigidly secured to the upper surface of the flange 5 when the motor is positioned at the right hand side of the machine or to a corresponding flange carried by the plate 2 when positioned at the opposite end thereof, and is of suitable shape to house the operative parts of the motor. The flange 5 is provided with a pair of upwardly extending laterally spaced standards 98 and 99 in which is journaled a horizontally extending motor shaft 100, bronze or other suitable bushings 101 being preferably disposed about the shaft where it passes through the standards. At its inner end this shaft projects for a suitable distance beyond the adjacent standard 60 and is operative to support the pinion 40 which is pinned or otherwise secured thereto so as to rotate therewith, while at its opposite end which also projects beyond the adjacent standard, a knob 102 is preferably disposed.

Positioned and freely rotatable on the shaft between the standards is a drum 103, one end of which, conveniently the inner end, is squared as at 104 to receive a correspondingly squared opening formed in the circular pawl plate 105 in such manner that when the plate is mounted on the drum, as best shown in Fig. 9, it will be constrained to rotate therewith. Adjacent the opposite end of the collar are mounted a pair of laterally spaced spring-guide plates 106, 107 which may either be arranged to turn with the drum or relatively thereto as may be preferred, the distance between the plate 106 and the plate 105 being preferably substantially equal to the width of the belt 90, one end of which is attached in any suitable way, as by a screw or rivet 108, to the drum and thence coiled about the drum for a plurality of turns and led through the opening 91 to the lay of the loom.

Also positioned on the shaft 100 and preferably between that end of the drum carrying the pawl plate and the face of the standard 98, is a ratchet wheel 110 which is keyed or otherwise secured to the shaft so as to turn therewith but in such manner as to permit the shaft to be slid through the wheel, while a pawl 111 is pivoted in proper position to engage the teeth of the ratchet wheel upon a suitable pivot screw 112 carried by the pawl plate 105, a flat spring 113 having one end disposed in slotted pins 114 carried by the plate and the other end bearing on the free end of the pawl serving to constantly press the nose of the latter into engagement with the teeth. The relative position of the pawl and teeth of the ratchet wheel is such that when the belt 90 is pulled in the direction of the arrow in Fig. 10 by the movement of the lay, the pawl will hold the ratchet wheel, and in turn the shaft 100 to which it is keyed, in relatively stationary position with respect to the drum 103 so that the continued drawing off of the belt will cause the shaft and pinion 40 to rotate in clockwise direction when viewed as in Fig. 10. Means are also provided for rewinding the belt on the drum during the return motion of the lay, said means preferably comprising a flat spring 115 coiled about the drum between the spring-guide plates 106 and 107. The inner end of this spring is suitably secured to the drum, conveniently by hooking it into a slot therein, while its outer end is provided with a loop 116 which surrounds a pin 117 rigidly supported in the standard 99 and a lug 118 formed integrally with the base or in any other suitable way, the spring being coiled on the drum in such direction that when the belt is drawn off so as to rotate the shaft 100 the spring will be wound up so that on the opposite movement of the lay the belt will be re-wound on the drum by the expansion of the 130

spring, the pawl during this operation running over the ratchet teeth and the drum revolving on the shaft 100 in anti-clockwise direction. It will thus be apparent that each time the lay moves in a direction away from the motor, the shaft 100 will be rotated as long as such movement is continued and that on the return movement of the lay the belt will be rewound on the drum while the shaft 100 remains stationary.

Means are also provided for moving the pinion 40 out of alignment with the gears 36, 36' so as to permit the latter to be swung from normal position to that shown in Fig. 4 and for this purpose I preferably arrange the shaft 100 for longitudinal as well as rotative movement in its supporting bushings, so that by grasping the knob 102 the shaft may be slid from the position shown in full lines in Fig. 9 to the position shown in dotted lines therein, thereby moving the pinion 40 from alignment with the gears 36, 36', the drum, ratchet wheel and adjacent parts of the motor being prevented from similar longitudinal movement through engagement with the standards 98 and 99. It will of course be understood that the keyway 120 formed in the shaft for the reception of the key 121 by which the ratchet wheel is secured thereto is of sufficient length to permit the requisite sliding movement of the shaft in moving from normal to dotted line position.

For retaining the shaft in normal position so as to prevent accidental disengagement of the pinion 40 from the gears 36, 36', I preferably provide a latch 125 pivoted on a pivot screw 126 carried by the housing and operative to engage within a groove 127 formed in that portion of the shaft which projects beyond the housing in such manner that when the latch is down as shown in Fig. 2 longitudinal movement of the shaft is prevented and the parts maintained in full line position but when the latch is lifted out of engagement with the shaft the latter can be slid to dotted line position.

The machine is adapted for attachment to the beam B of the loom as already explained and for the purpose of supporting the fabric under that part of the device which overhangs the rear face of the beam and thereby relieving the mechanism from undue strain, I preferably provide suitable fabric supporting means which may conveniently consist of a bar or block of wood B' secured to the face of the beam between the end members 2 and 3 by lag screws L or in any other suitable manner, so that its upper surface is in alignment with the upper surface of the beam, the heads of the screws being countersunk so as to in effect provide an extension of the beam affording a smooth surface for the passage of the fabric which during the weaving operation is drawn over the block

and thence downwardly to the take-up roll in the manner shown in Fig. 4. In the operation of the machine a plurality of cutters equal in number to the number of floats which are to be cut are employed, each cutter being adjusted to cut one float as it is fed to the cutter from the loom, the cutters on the two shafts being so arranged that those on shaft 18' align with the spaces between those on shaft 18, so that the forward set of cutters driven from the cutter shaft 18 are operative to cut every other row of the float and the rear set of cutters driven from the shaft 18' are operative to cut the alternate rows left uncut by the first set. The foot of each cutter body is operative to enter and afford support to the body of a cutter nose from the forward extremity of which the pile wire is led back through the loom in the usual manner. Over this wire the weft loops or floats are formed in the weaving operation and after formation are fed toward the loom beam and pass over the split cutter noses which, owing to their lateral bowed or curved form and resilient construction, effect a lateral stretching of the loops so that when the latter are presented to the cutters they are in stretched or relatively taut condition and disposed equidistantly on each side of the cutter blade so that the cutting operation is performed at substantially the exact center of each loop.

If at any time it be found that adjustment of any of the cutters is required in order to bring them into properly aligned relation with their respective floats, it is only necessary to loosen the bolt 69 which holds the block 68 adjacent to that cutter which is to be adjusted to permit the cutter to be moved to the right or left without removing it from the machine for a sufficient distance to bring it into proper position, the driving gear and guide plate for that particular cutter readily following the cutter to its new position by reason of their capability of free longitudinal movement on the driving shaft.

Should it, however, at any time become necessary to entirely remove one or more of the cutters from the machine by reason of the cutter having become bent, dulled or otherwise unsuitable for further operation, the set screws 30 are loosened in the latches 28 and 29 which secure the housing plates carrying the driving shaft from which that particular cutter is driven, the latches raised and the housing plates, tie rod and shaft swung forward to the position illustrated in Fig. 4 in which both shafts are shown as having been moved in the manner described. It will be evident, however, that in order to permit the shaft 18' to be so moved, the pinion 40 must first be withdrawn from alignment with the gear 36' which operation can be readily effected by sliding the

motor shaft 100 outwardly in the manner previously described.

With the parts in the position shown in Fig. 4 any one or more of the cutters in either series may be readily removed from the machine by first taking off the adjacent clamping block 68 and then lifting the cutter body upwardly and forwardly in the manner indicated until it will clear the bar 15, after which the cutter may be lifted upwardly and rearwardly entirely free of the machine. During this operation, however, the cutter nose which is connected to the pile wire and upon which are ordinarily disposed a plurality of weft loops or floats disengages from the cutter body and remains in position in the fabric, thus enabling the foot of the new cutter to be readily inserted in the body of the nose and the cutter re-clamped in position without in any way disturbing the fabric or leaving any uncut loops. The new cutter having been inserted and clamped in place, the housing plates are again raised to normal position and secured therein, thus again putting the machine into condition for operation. This ability to remove a single cutter without in any way disturbing the fabric or leaving any uncut loops is of great utility.

It will of course be understood from the foregoing description that in operation both driving shafts are rotated in the same direction through the operation of the motor but with an intermittent motion since the driving shaft 100 is only rotated while the belt 90 is being drawn off the drum by the movement of the lay in one direction but as at each reciprocation of the lay but a single loop is added to the fabric and a single loop in turn forced against each cutter, the latter, even though driven intermittently, are entirely effective to perform the cutting operation.

Additionally, by the employment of a plurality of series of cutters in which the cutters of one series are located in alignment with the spaces between the cutters in the other series, I am enabled to produce a machine which will operate efficiently on those classes of fabrics in which the rows of weft loops or floats are spaced very closely together and which it would be impossible to cut satisfactorily in machines in which the cutters are arranged in a single row or series by reason of the inherent and necessary thickness of the cutters themselves which prevents their being placed sufficiently close together to operate on fabrics of this character.

While I have herein described with considerable particularity a preferred embodiment of my invention and have described its operation in connection with a loom in which the floats or weft loops of the fabric are formed over pile wires, it will be understood that the invention may be used with

equal facility in connection with other forms of leaders and in the production of various classes and sorts of fabrics, and additionally, that the various elements of the machine and the construction, design and arrangement thereof may be modified from the precise embodiment shown without departing from the spirit and scope of the invention as defined in the appended claims.

Having thus described my invention, I claim and desire to protect by Letters Patent of the United States:

1. In a machine for cutting pile fabrics, the combination of a plurality of drive shafts, means for driving the shafts, a plurality of circular cutter blades supported adjacent each shaft, and means carried by each shaft operative to effect an independent drive of each of the adjacent cutter blades therefrom.

2. In a machine for cutting pile fabrics, the combination of a plurality of drive shafts, means for rotating the shafts, a plurality of circular cutter blades independently supported adjacent each shaft and each having a gear in association therewith, and a plurality of gears supported on and rotatable with each of said shafts and each operative to mesh with one of said first mentioned gears to effect the drive of the cutter blade adjacent thereto.

3. In a machine for cutting pile fabrics, the combination of a drive shaft, means for rotating the shaft, a plurality of independent gears supported on and rotatable with the shaft, a plurality of circular cutter blades in number equal to the number of said gears, means for supporting said blades, and a gear rotatable with each blade and adapted to mesh with one of the gears on the shaft.

4. In a machine for cutting pile fabrics, the combination of a drive shaft, means for rotating the shaft, a plurality of independent gears supported on and rotatable with the shaft, a guide plate rotatable with each gear and having a portion laterally spaced therefrom, a plurality of circular cutter blades in number equal to the number of said gears and each having a gear fixedly secured thereto and rotatable therewith, and means for supporting each cutter blade in such position that the periphery thereof will enter the space between one of the gears on said drive shaft and its adjacent guide plate with the gear secured to each cutter blade in meshed relation with one of the gears on the shaft.

5. In a machine for cutting pile fabrics, the combination of a drive shaft, means for rotating the shaft, a plurality of circular cutter blades, means for independently supporting each of said blades adjacent the shaft, a gear rotatable with each blade, and a plurality of gears equal in number to the

cutter blades carried by, rotatable with and freely longitudinally movable on the drive shaft and respectively adapted for operative engagement with the gears carried by 5 said cutter blades to effect rotation of the blades in correspondence with the rotation of the shaft.

6. In a machine for cutting pile fabrics, the combination of a drive shaft, means for 10 rotating the shaft, a plurality of circular cutter blades, a gear rotatable with each blade, a plurality of gears carried by, rotatable with and freely longitudinally movable on said shaft, a guide plate carried by 15 each of said last mentioned gears and offset from the face thereof to provide a guide slot, and means for operatively supporting each of said cutter blades with the gear carried thereby in intermeshed relation with 20 one of the gears on the drive shaft and with the periphery of the cutter blade within said slot.

7. In a machine for cutting pile fabrics, the combination of a plurality of drive 25 shafts, means for supporting said shafts in parallel relation one behind the other, a plurality of independent cutters having circular cutter blades, means for supporting a predetermined number of said cutters adjacent each of said shafts, and means for effecting the simultaneous rotation of the 30 blades of each series of cutters from the adjacent drive shaft.

8. In a machine for cutting pile fabrics, the combination of a plurality of drive 35 shafts, means for supporting said shafts in parallel relation one behind the other, a plurality of independent cutters having circular cutter blades, means for supporting a predetermined number of said cutters in laterally spaced relation adjacent one of said 40 shafts, and means for supporting a predetermined number of said cutters in laterally spaced relation adjacent the other of said 45 shafts with the blades thereof in aligned relation with the spaces between the blades of the first mentioned cutters, and means for effecting the rotation of each series of cutter blades from the adjacent drive shaft.

50 9. In a machine for cutting pile fabrics the combination of a plurality of drive shafts, means for supporting said shafts in parallel relation one behind the other, a plurality of independent cutters having circular cutter blades, means for supporting a predetermined number of said cutters in laterally spaced relation adjacent one of said shafts and means for supporting a predetermined number of said cutters in laterally spaced relation adjacent the other of said 55 shafts with the blades thereof in aligned relation with the spaces between the blades of the first mentioned cutters, means for rotating the cutter blades comprising a plurality of gears mounted on and rotatable

with each shaft and in number equal to the number of cutter blades adjacent thereto, and a gear rotatable with each cutter adapted to mesh with one of the gears on the adjacent shaft.

70 10. In a machine for cutting pile fabrics, the combination of a drive shaft, means for supporting said shaft in a plurality of positions, a circular cutter blade, a gear carried thereby, means for supporting the cutter blade, a gear carried by the shaft and adapted to mesh with the gear carried by the cutter blade when the shaft is in one position, and means for removably securing said shaft in said position.

75 11. In a machine for cutting pile fabrics, the combination of a plurality of circular cutter blades, a gear carried by each blade, means for supporting said cutters in an aligned series, a drive shaft, a plurality of gears carried by said shaft and rotatable therewith, and means for supporting said shaft adapted to permit said shaft to be swung from a position substantially above the series of cutters and in which the gears 80 thereon are in operatively meshed relation with the gears on the subjacent cutter blades to a position without the vertical plane passing through centers of the cutter blade to allow the cutter blades to be removed from their supporting means.

85 12. In a machine for cutting pile fabrics, a rotatable circular cutter blade, a cutter body pivotally secured thereto and having a head adapted for attachment to supporting means and a foot provided with a laterally extending projection and arranged to receive and detachably support a cutter nose adapted for connection to a leader.

90 13. In a machine for cutting pile fabrics, a cutter comprising a circular rotatable blade, a body pivoted thereto and having a head adapted for engagement with supporting means and a foot extending partially beneath said blade, having a laterally extending projection and operative to receive and detachably support a cutter nose adapted for connection to a leader.

95 14. In a machine for cutting pile fabrics, a cutter comprising a circular blade, a body having a portion lying adjacent one face of the blade and another portion laterally offset with respect to the first mentioned portion and lying substantially in the plane of the blade, and a pivot rotatably securing the blade to the first mentioned portion.

100 15. In a machine for cutting pile fabrics, a cutter comprising a circular blade, a body having a portion disposed adjacent one face of the blade, a laterally offset portion extending beyond the periphery of the blade and having a head adapted for engagement with cutter supporting means and a foot extending partially beneath the blade and arranged to support a cutter nose, and a pivot 105

rotatably securing said blade to said first mentioned portion.

16. In a machine for cutting pile fabrics, the combination of a circular cutting blade, a cutter body pivotally secured to said blade, and a cutter nose having a portion detachably secured to the body and a split portion extending beneath the blade and adapted for attachment to a leader.

17. In a machine for cutting pile fabrics, the combination of a circular cutting blade, a cutter body pivotally secured to said blade, and a cutter nose having a portion detachably secured to the body and a split, laterally bowed portion extending beneath the blade and adapted at its forward extremity for attachment to a leader.

18. In a machine for cutting pile fabrics, the combination of a circular cutting blade, a cutter body comprising a portion pivotally secured to the blade and disposed adjacent one face thereof and an offset portion disposed substantially in the plane of the blade, said offset portion comprising a part adapted for engagement with supporting means and a part adapted to receive a cutter nose, and a cutter nose removably supported on and embracing said last mentioned part and having a split, laterally bowed portion extending beneath the blade and adapted for attachment at its extremity to a leader.

19. In a machine for cutting pile fabrics, the combination of a circular cutting blade, a cutter body comprising a portion pivotally secured to the blade and disposed adjacent one face thereof and an offset portion disposed substantially in the plane of the blade, said offset portion comprising a part adapted for engagement with supporting means and a part adapted to receive a cutter nose, a cutter nose removably supported on and embracing said last mentioned part and having a split, laterally bowed portion extending beneath the blade and adapted for attachment at its extremity to a leader, and means carried by the body and cooperative with a notch in said nose for effecting operative registration of the body and the nose when the former is introduced into the latter.

20. In a machine for cutting pile fabrics, the combination of a pair of end members adapted for attachment to the beam of a loom, a cutter supporting bar extending between the members and having a rib, a plurality of cutters disposed adjacent the bar and each having a blade and a portion engaging said rib, a plurality of independent clamping blocks removably positioned on said bar, each block being adapted to engage a predetermined number of said cutters, means for individually securing the clamping blocks to the bar, a driving shaft, means for effecting rotation of the cutter blades

from said shaft, and means for movably supporting said shaft from said end members.

21. In a machine for cutting pile fabrics, the combination of a pair of end members 70 adapted for attachment to the beam of a loom, a cutter supporting bar extending between the members and having a rib, a plurality of cutters disposed adjacent the bar and each having a blade and a portion engaging said rib, a plurality of clamping blocks disposed on said bar each adapted to engage a plurality of the cutters, means for removably clamping each block against the bar and the cutters to hold the latter in 80 operative position, a driving shaft normally operatively disposed substantially in the vertical plane of the cutter blades, means for effecting the rotation of the blades from said shaft, and means carried by said end members 85 for supporting said shaft and arranged to permit movement of said shaft out of the vertical plane of the cutter blades.

22. In a machine for cutting pile fabrics adapted for attachment to the beam of a 90 loom having a lay, means for actuating the cutting elements of the machine comprising a rotatable shaft, a sleeve mounted thereon, a belt coiled about the sleeve and having one end adapted for attachment to the lay, means for causing said shaft to rotate unitarily with the sleeve when the belt is drawn therefrom in one direction, and means for rotating the sleeve to re-coil the belt thereon when the belt is moved in the other direc- 100

23. In a machine for cutting pile fabrics adapted for attachment to the beam of a loom having a lay, means for actuating the cutting elements of the machine comprising 105 a rotatable shaft, means for supporting said shaft, a sleeve disposed on said shaft, a belt connected with said sleeve at one end and adapted for connection with the lay of the loom at the other, a ratchet wheel rotatable with the shaft, a pawl carried by the sleeve and cooperative therewith to cause the shaft to rotate with the sleeve when the belt is drawn off therefrom in one direction, and a spring coiled about the sleeve and operative 110 to rotate said sleeve with respect to the shaft to rewind the belt on the sleeve when the belt is moved in the opposite direction.

24. The combination with a machine for cutting pile fabrics and adapted for attachment to the beam of a loom having a lay, of means for actuating the cutting elements of the machine from the lay comprising a rotatable shaft, means for supporting the shaft, a sleeve loosely disposed on the shaft, a belt wound about the sleeve and adapted for connection to the lay, a ratchet wheel carried by and rotatable with the shaft, a pawl supported from the sleeve and cooperative with the ratchet wheel to lock 120

the sleeve and shaft together when the belt is moved in one direction, and means comprising a flat spring coiled about the sleeve and operative to effect relative rotation between the sleeve and the shaft when the belt is moved in the other direction to thereby rewind the belt on the sleeve.

25. The combination with a machine for cutting pile fabrics and adapted for attachment to the beam of a loom having a lay, of means for actuating the cutting elements of the machine from the lay comprising a rotatable and longitudinally movable shaft, means for supporting the shaft, a sleeve loosely disposed on the shaft, a belt wound about the sleeve and adapted for connection to the lay, a ratchet wheel carried by and rotatable with the shaft, a pawl supported from the sleeve and cooperative with the ratchet wheel to lock the sleeve and shaft together when the belt is moved in one direction, and means comprising a flat spring coiled about the sleeve and operative to effect relative rotation between the sleeve and the shaft when the belt is moved in the other direction to thereby rewind the belt on the sleeve, and means for operatively maintaining said shaft at the limit of its longitudinal movement in one direction with respect to said supports.

26. Actuating means for pile cutting mechanism comprising a shaft, means for supporting said shaft, a sleeve disposed on said shaft and rotatable with respect thereto, a belt coiled on said sleeve in one direction and a spring coiled thereon in the other direction, and means operative to cause the sleeve and shaft to turn together as a unit when the belt is drawn off of the sleeve and to permit the relative rotation of the sleeve and the shaft under the influence of said spring when the pull on the belt is relieved.

27. Actuating means for pile cutting mechanism comprising a rotatable and longitudinally movable shaft, means for supporting the shaft, a sleeve disposed on the shaft and rotatable with respect thereto, a belt coiled on the sleeve, a flat spring coiled on the sleeve in the opposite direction to the belt, means operative to cause the sleeve and shaft to turn together as a unit when the belt is unwound from the sleeve against the resistance of the spring and to permit the sleeve to rotate with respect to the shaft to rewind the belt thereon by the expansion of

the spring when the pull on the belt is released, and releasable means normally operative to prevent longitudinal movement of the shaft with respect to said supports and said sleeve.

60

28. A machine for cutting pile fabrics and adapted for attachment to a loom, comprising a plurality of cutters each having a rotatable blade, a body portion and a detachable nose adapted for connection to a leader over which the weft loops of the fabric are formed by the loom, means for supporting the cutters in laterally spaced relation, means for rotating the blades of the individual cutters and means whereby the cutter blades may be selectively detached from or replaced in the cutter noses without disturbing the position of the latter with respect to the fabric.

70

29. A machine for cutting pile fabrics and adapted for attachment to a loom, comprising a plurality of cutters each having a rotatable blade, a body portion and a nose detachable therefrom, said nose comprising a split portion extending beneath the blade and adapted for attachment to a leader over which the float of the fabric is formed by the loom and to receive the loops of the float, means for supporting the cutters in laterally spaced adjusted relation, and means for rotating the cutter blades, said cutter blades and bodies being arranged for selective detachment from or replacement in their respective noses without disturbing the relative position of the nose and the fabric.

80

30. A machine for cutting pile fabrics and adapted for attachment to a loom, said machine comprising a plurality of cutters each having a rotatable blade, a body portion and a detachable nose, a portion of said nose being split to receive the blade and adapted to enter weft loops of the fabric as the latter is formed on the loom, means for supporting the cutters in individually aligned relation with said loops, means for rotating the cutter blades and means whereby the cutter blades and bodies may be selectively detached from or inserted into their respective cutter noses without disturbing the relative position of the latter with respect to the fabric.

95

In witness whereof, I have hereunto set my hand this 10th day of May, 1922.

GEORGE SEYMOUR.
